UNITED STATES PATENT OFFICE.

ROBERT WINTER, OF HANOVER, GERMANY.

DAMPER.

SPECIFICATION forming part of Letters Patent No. 700,396, dated May 20, 1902.

Application filed June 22, 1901. Serial No. 65,610. (No model.)

To all whom it may concern:

Be it known that I, ROBERT WINTER, a subject of the German Emperor, and a resident of Hanover, Germany, have invented certain new and useful Improvements in Dampers, of which the following is a specification.

This invention relates to dampers for stoves; and it consists in the combination of a damper in the stove exit-flue for regulating the draft, 10 with a door regulating the admission of air.

In the accompanying drawings, Figure 1 is a central vertical sectional view of the stove, taken on the line D D of Fig. 2 and Fig. 5. Fig. 2 is a transverse vertical sectional view 15 taken on the line A A of Fig. 1 with the stove partly broken away. Fig. 3 is a horizontal sectional view taken on the line C C of Fig. 2. Fig. 4 is a like view taken on the line C C of Fig. 1. Fig. 5 is a horizontal sectional view 20 taken on the line E E of Fig. 1. Fig. 6 is a front elevation of the draft-door, the stove being broken away. Fig. 7 is a detail perspective view of a part of the spindle, showing a handle connected thereto for turning the 25 same.

The hollow spindle *e* of the damper *c* passes through the stovepipe *m*. The upper portion of the spindle *e* has a slot *a* formed therein, which when open permits the admission 30 of air necessary to slow combustion, as shown in Fig. 3. A metallic plate *g* is provided for the purpose of closing the slot *a*, thus allowing no air to be admitted into pipe *m*. The hollow spindle *e* has a slot in its lower portion, 35 through which the air enters into the said spindle, up through the same, and out at the top thereof.

In the lower end of hollow spindle *e* the spindle *b* is placed and is pivoted in the bottom 40 of the stove and carries a toothed section *s* and an arm *t* in order to operate the door *k* of the ash-box when required. This door is pivotally secured at its upper end and has a lateral movement on its pivot. Thus when the 45 door is operated to move laterally the steps *u*, when door *k* bears against the projection *l* of the stove, permit a certain amount of air to enter, according to the distance the door has moved. The toothed sector *s* and the 50 toothed rack *z*, arranged on the door, are used to effect this lateral movement. The arm *t*,

Figs. 1 and 5, after the door has reached the limit of its lateral movement, bears against the oblique face *v* of the door and raises the latter, so as to obtain a quantity of air necessary to a strong combustion. 55

In the positions shown in Figs. 3 and 5 the door and the damper are closed and allow a secondary current of air to pass into the stove exit-flue. If the spindle *b* be turned toward the left, the damper *c* gradually opens the exit-flue, the slot *a* is gradually closed, while the door is first given a lateral movement and is then raised. Simultaneously with the closing of the damper by the turning of spindle 60 *d* to the right the door falls lower and lower and is then finally closed by the lateral movement imparted thereto. 65

In Fig. 7 I have shown a part of the spindle *b* with a handle *b'* connected thereto for rotating the spindle to actuate the spindle *e*. This means is not shown on the spindle *b* in Fig. 1, as other means than this may be employed, any suitable construction by means of which partial rotation may be imparted to 70 the spindle being applicable. 75

Having fully described my invention, what I desire to secure by Letters Patent is—

1. The combination of a stove having an exit-flue and a draft-opening with a damper 80 in said exit-flue having a hollow spindle extending through the walls thereof and communicating with the external air, said spindle being provided with an aperture within the exit-flue, and said flue being provided with a 85 plate adapted to close said aperture when the damper is opened, a pivoted draft-door adapted to close said draft-opening and carrying a rack and a rod connected to said damper-spindle and provided with a gear-sector adapted 90 to mesh with the rack on the draft-door.

2. In a damper for stoves, the combination of a stove having an exit-flue and a draft-opening with a damper in said exit-flue, having a hollow spindle extending through the walls 95 thereof and communicating with the external air, said spindle being provided with an aperture within the exit-flue, and a plate in said exit-flue adapted to close said aperture when the damper is opened, a rod connected to said hollow spindle and pivoted in the stove-bottom, a gear-sector mounted on said rod and 100

carrying an arm, and a pivoted draft-door, adapted to close the draft-opening and carrying a rack which meshes with the gear-sector when the rod is rotated to move the door laterally, the said door being raised when engaged by the arm carried by the gear-sector, substantially as described.

In testimony whereof I have hereunto set my hand in presence of two witnesses.

ROBERT WINTER.
